(57) **CLAIM**

I claim the ornamental design for a berm walkway, as shown and described.

DESCRIPTION

FIG. 1 is a perspective view of a berm walkway, showing my new design in a deployed configuration;

FIG. 2 is a front elevational view of FIG. 1, the rear elevational view being a mirror image thereof;

FIG. 3 is a top plan view of FIG. 1;

FIG. 4 is a bottom plan view of FIG. 1;

FIG. 5 is a left-side elevational view of FIG. 1, the right-side elevational view being a mirror image thereof; and,

FIG. 6 is a perspective view thereof, illustrated in a collapsed configuration.

The broken lines showing a sand berm in FIG. 1 depict environmental matter and form no part of the claimed design.
